LABEL FOLDING METHOD AND MEANS

Gustave A. Piepenbring, Stratford, Conn., assignor to American Fabrics Company, Bridgeport, Conn., a corporation of Connecticut

Application September 26, 1931, Serial No. 565,244

21 Claims. (Cl. 270—61)

My invention relates to improvements in methods of folding labels at opposite margins thereof and to improved means for carrying out said methods, having for an object to insure square 5 folds such that the folded margins will be parallel.

The invention is particularly adapted for folding machines in which there is a relative movement of a label with respect to the folders and in a direction lengthwise of the margins to be 10 folded. Such a machine, for example is that invented jointly by Werner Beutel and myself and disclosed in a copending application Serial No. 469,016, filed July 19, 1930. In said machine the labels are cut from a continuous strip and the 15 cut-off portions are seized by a pair of jaws with the cut margins projecting from opposite sides of the jaws. The jaws are then advanced to carry the projecting margins through a pair of folders similar to the hemming folders used on sewing 20 machines and thence into a pair of heated presses so that the margins are first folded and then ironed.

Occasionally difficulty is experienced in folding light and flimsy material. When the cut 25 margins are drawn through the folders there is a dragging action on the material which tends to crumple the material or distort it swinging the margins inward or in a direction away from the folders so that the folds are usually deeper at the 30 forward edge of the label than at the rear edge. While this tendency to distortion is negligible with heavy or stiff material it is very prevalent with flimsy or light material producing labels which, as they come from the machine, are not 35 rectangular but take the form of a trapezium.

Sometimes distorted folding results from uneven tension in the weave. If the warp threads on one side are under greater tension than those on the other the label assumes a curved form 40 and the folded margins will tend to be substantially radial to the curvature.

It is an object of the present invention to overcome the difficulties above named by forcing an increased amount of material into the folders on 45 the side which is or tends to become longer, or, conversely, to reduce the amount of material introduced into the folders on the side which is or tends to become shorter during the folding operation.

More specifically my invention provides means 50 for ripping or crimping the label to shorten the forward edge (or the rear edge as the case may be) while it is being passed through the folders, so that after it has been flattened out after ironing, its folded ends will be substantially parallel.

With these objects in view and others which will appear hereinafter, I shall now describe a preferred embodiment of my invention and thereafter the novelty and scope of the invention will be pointed out in the claims.

In the accompanying drawing:

Figure 1 is a view in side elevation and partly in section of a portion of a label cutting and folding machine embodying my invention;

Fig. 2 is a view on an enlarged scale of a portion 65 of Fig. 1, and represents a longitudinal section taken through the clamping jaws of the machine;

Fig. 3 is a view in section taken on the line 3—3 of Fig. 2 and showing one of the folders in end elevation with a margin of a label passing there- 70 through;

Fig. 4 is a top plan view of the lower clamp- ing jaw;

Fig. 5 is a view in perspective of a label show- 75 ing how it is crimped while being passed through the folders;

Fig. 6 is a view in perspective of the same label after the folds have been ironed and the label has been flattened out;

Fig. 7 is a view in transverse section through 80 the clamping jaws of a modified form of the invention; and

Fig. 8 is a plan view of a label showing the manner in which it is crimped by the jaws shown 85 in Fig. 7.

The label cutting and folding machine which is shown fragmentally in Fig. 1 is substantially the same as that disclosed in said copending application except for the construction of the clamping jaws. The machine comprises a main 90 frame 10 provided with horizontal ways 11 in which a carriage 12 is adapted to slide. The carriage is reciprocated by rod 13 which is connected to a cam operated lever (not shown).

The carriage 12 has fixed thereto a lower 95 clamping arm 14. An upper clamping arm 15 is pivoted to the carriage on a stud 16. A slotted rearward extension 17 of the arm 15 engages a pin 18 projecting from a vertical slide bar 19. This bar is arranged to slide in ways 20 provided 100 on the carriage 12. Thus by movement of the bar 19 up and down the arm 15 may be oscillated toward and from the arm 14. To effect vertical movement of the bar 19 the latter is provided with a roller 21 which engages a hori- 105 zontal slot 22 formed in a member 23, the lat- ter being mounted to slide vertically on ways 24 fixed to the main frame 10. The member 23 is also provided with a slot 25 engaged by a roller 26 on one arm of a cam lever 27 which is pivoted 110

at 28 to a pedestal 29 forming part of the main frame 10. The lever 27 is oscillated to raise and lower the member 23, in timed relation to the movement of the carriage 12, by suitable cam mechanism (not shown).

The label strip is fed between the arms 14 and 15 when they are in open position, and it enters in a direction at right angles to the movement of the carriage 12. When a sufficient length of label 10 has been fed between the arms it is cut off by a knife indicated by broken lines at 30. The arm 15 then is swung downward so that the label is firmly gripped between clamping jaws provided on the arms 14 and 15. The label is then carried 15 toward the left, as viewed in Fig. 1, by operation of the rod 13. In its course, the cut ends of the label which project from opposite sides of the jaws are fed through a pair of folders 32 and thence on to a pair of presses 33. Only one of 20 the folders and presses is shown in Fig. 1, but it will be understood that the same mechanism is duplicated on the opposite end of the label. The folder comprises a spirally grooved member 34 supported on a post 35 carried by the main 25 frame 10. The groove is widely flared at the mouth and at the exit end merges into a constricted horizontal groove defined by upper and lower spring fingers 34a. Thus as a label end enters the groove it is curled over thereby and then flattened into a fold between the fingers 30 34a. A flat guide 36 upwardly bent at its rear end fits into the groove and serves to define the edge of the fold. This guide is resiliently supported by curved spring bracket 37.

The folders lie immediately adjacent the 35 presses 33 so that as the folded ends of the label pass out of the folders they immediately enter the presses. Each press comprises a fixed anvil 38 and a vertically reciprocable ironing member 39. The latter is spring-pressed downward but 40 is raised by a crank arm 40 to receive the folded end of the label. The arm 40 engages a pin 41 carried by the member 39 and is operated by suitable mechanism not shown. As soon as the 45 label enters the press the arm 40 is lowered and the member 39 comes down upon the folded margin of the label. Suitable means are provided for heating the member 39 so that the fold will be ironed.

As soon as the arms 14 and 15 have delivered 50 the label to the presses the arm 15 is raised and the carriage 12 is withdrawn to bring the clamping jaws into position to receive the next label. When the next label is advanced into the presses, 55 the previous label is pushed out of the presses by the jaws, as will be described more fully hereinafter, and the ejected label is thus fed between a pair of rollers 42 and 43 which discharge it from the machine, or deposit it in a suitable receptacle not shown.

The mechanism so far described corresponds 60 substantially to that disclosed in said copending application. The novelty of the present invention lies particularly in the form of the clamping jaws.

Referring first to the lower jaw it will be observed that the latter is formed with a laterally extending plate 45 which is attached to the arm 14 by an angle bracket 46. The plate 45 is formed with a central rib 47 projecting from its forward edge, and at either side of this rib but spaced slightly therefrom are slots 48 which extend through the bracket 46. Each slot 48 opens 75 into a groove 48a of slightly greater width and

much greater length than the slot. Each groove 48a extends to the forward edge of the plate 45 for a purpose that will be explained hereinafter. On the upper face of the plate along opposite side edges, but stepped back from the front edge of the plate, are two toothed ribs 49. The rear end 80 50 of the plate 45 is bent downwardly and terminates near the point where the arm 14 attaches to the carriage 12.

The upper arm 15 is provided with a plate 55 which corresponds in general form to the plate 45 and is attached to the arm 15 by an angle bracket 56. The plate 55 is provided on its under face with a central rib 57 which is adapted to register with the rib 47. At opposite sides of the rib 57 are slots 58 which pass through the plate 55 and the angle bracket 56 and these slots are aligned with the slots 48 in the lower jaw. Along opposite margins of the plate 55 are toothed ribs 59 which are adapted to register with the ribs 49 of the lower jaw. The rear end of the plate 55 is in the form of an upwardly bent extension 60. The purpose of these extensions 50 and 60 will be explained presently.

As shown in Fig. 4, the rib 47 extends from the 100 forward margin of the plate 45 to a point near the middle of the slots 48, while the ribs 49 begin at their forward ends at a point beyond the middle of the slots 48 and extend well to the rear of said slots. The arrangement of the central and marginal toothed ribs of the upper jaw is substantially the same. The purpose of these ribs is to provide a three point engagement of the label. A label in gripped position is indicated by broken lines in Fig. 4. It will be observed that the label is centrally gripped between the ribs 57 and 47 at its forward edge, and is engaged by the toothed ribs 59 and 49 at its rear edge and near its cut ends.

Mounted on the bracket 56 and symmetrically disposed with respect to the slots 58 is a block 62. 115 Supported on this block is a U-shaped die 63, the legs of which project through the slots 58 and also (when the jaws are closed) into the slots 48. The lower ends of these legs are cut on a slant as clearly shown in Fig. 2, so that when the jaws are 120 closed only the forward part of the legs will project into the slots 48. The member 63 is arranged to be adjusted forwardly or rearwardly on the jaw 15 and to this end it is formed with a slot 64 through which passes a screw 65 that fastens it to 125 the block 62.

In use when the jaws are closed a label gripped therebetween will be pressed into the lower slots 48 by the legs of the member 63, thereby crimping the forward edge of the label as shown in Fig. 131 5. The extent to which the label is crimped may be regulated by adjusting the position of the member 63. Thus, if said member is moved rearwardly the crimping will be deepened whereas if it is moved forwardly the crimping will be more shallow. Obviously if the slots in the jaws and the adjusting slot 64 were long enough the die could be moved forward so far as not to crimp the edge of the label at all. When the label is being crimped, as shown in Figs. 2 and 3, it is gripped 135 centrally at its forward edge, between the die legs so that the forward portion of the label is free to assume the crimped form. At the same time the rear portion of the label is held taut by the toothed ribs 49 and 59. As a result, while the label 140 is clamped between the jaws the forward edge of the label is effectually shortened and the cut ends are not parallel to the line of travel but flare outwardly from a narrower leading edge to a wider trailing edge. Thus when the label is advanced 145 150

between the folders there will be less material pushed into the folder at the leading edge of the label than at the trailing edge, and the dragging action which tends to produce a narrower fold at the trailing edge is offset. A substantially square fold results, i. e., a fold of substantially uniform width throughout its length, so that when the label is flattened out, as shown in Fig. 6, the folded margins will lie parallel one to the other.

If desired a die 63 of other inclination than that illustrated may be used, the selection of the die being made according to the condition of the material passed through the machine. If the tendency should be the reverse to that described above the die 63 may be reversed so that the downward slant of its legs will be toward the rear rather than forward. It will also be understood that the die may be set in a central position for a normal condition of the material and may be adjusted in one direction or the other according to the direction in which the condition of the material varies from normal.

The operation of the mechanism has already been described. However, I would here explain that the means for moving a previous label out of the presses consists in providing the brackets 46 and 56 with forward extensions 68 and 69 respectively. These extensions are bent oppositely at their extremities and when the jaws are closed they cooperate to form a vertical surface which serves as a pusher to push out the previous label. It will be understood that the brackets 56 and 46 are made of light resilient material so that when the jaws are in clamped position, the extensions 68 and 69 will be tightly engaged so that there will be no chance for a label to slip between them.

The purpose of the grooves 48a is to permit easy withdrawal of the plate 45 from a label after the latter has been introduced into the presses. The grooves prevent the plate from catching on the crimped forward edge of the label and dragging the label out of the press.

In order to save time in the operation of the machine the feed of tape under the knife 30 may take place while the carriage 12 is returning. The tail pieces 50 and 60 are provided to guide the projecting portion of the label strip into position between the jaws while the latter are returning to clamping position.

The modification shown in Fig. 7 will be readily understood. In place of the U-shaped dies 63, I provide a central die 70 which is adjustable forwardly and rearwardly in a slot formed in a clamping plate 71 and in a bracket 72 carried by the upper arm 15. The lower arm 14 is provided with a clamping plate 73 which is secured to said arm by an angle bracket 74. A central slot 75 is formed in the plate 73 and bracket 74 to receive the die 70 so that when the jaws are clamped together, as shown in Fig. 7, the label will be depressed by the die 70 into the slot 75. The die 70 is of semi-conical form with its apex extending rearwardly. The die therefore forms a crimp in the label such as indicated at 76 in Fig. 8.

The plate 73 is formed with ribs 77 at each side of the slot 75 but there are no corresponding ribs on the plate 71 so that the label is free to be crimped at its forward edge. However the rear edge of the label is securely gripped between marginal toothed ribs 78 and 79 formed on the plates 71 and 73 respectively. These ribs correspond in position and form to the ribs 59 and 49 of the embodiment described above.

While I have described two embodiments of my

invention, it will be understood that these are to be taken as illustrative and not limitative and that I reserve the right to make such changes in form, construction and arrangement of parts and method of procedure as will fall within the spirit and scope of the following claims.

I claim:

1. The method of folding an end of a label with a folder, which consists in distorting the body of the label to shorten a side edge of the same, causing relative edgewise movement of the label with respect to the folder so as to draw said end therethrough, and thereafter flattening the body of the label.

2. The method of folding an end of a label with a folder, which consists in distorting the body of the label to shorten a side edge of the same, causing relative edgewise movement of the label with respect to the folder so as to draw said end therethrough with the shortened edge in the lead, and thereafter flattening the body of the label.

3. The method of forming parallel folds at opposite ends of a label with a pair of folders, which consists in crimping the body of the label near one side edge to shorten said side edge, causing relative movement of the label edgewise between the folders to draw the ends of the label through said folders respectively, and thereafter flattening the body of the label.

4. The method of forming parallel folds at opposite ends of a label with a pair of folders, which consists in crimping the body of the label near one side edge to shorten said side edge, moving the label edgewise between the folders to draw the ends of the label through said folders respectively with the shortened side in the lead, and thereafter flattening the label.

5. In a label folding machine, a folder, means for moving a label edgewise relative thereto to draw an end of the label through the folder, and means for distorting the body of the label whereby the edge of said label end will diverge from parallel to the direction of movement of the label.

6. In a label folding machine, a folder, means for moving a label edgewise relative thereto to draw an end of the label through the folder, and means for distorting the body of the label whereby the edge of said label end will be angled outwardly toward the rear with respect to the direction of movement of the label.

7. In a label folding machine, a folder, a clamp for gripping a label with an end of the label projecting therefrom, means for moving the clamp to carry the label edgewise past said folder and draw said end through the folder, and means for controlling the relative length of the leading and trailing edges of the label.

8. In a label folding machine, a folder, a clamp for gripping a label with an end of the label projecting therefrom, means for moving the clamp to carry the label edgewise past the folder and draw said end through the folder, and means on the clamp for crimping the body of the label to vary the length of the leading edge with respect to that of the trailing edge thereof.

9. In a label folding machine, a folder, a clamp for gripping a label with an end of the label projecting therefrom, means for moving the clamp to carry the label edgewise past the folder and draw said end through the folder, and crimping means on the clamp for shortening the leading edge of the label.

10. In a label folding machine, a folder, a clamp for gripping a label with an end of the label projecting therefrom, means for moving the clamp

- to carry the label edgewise past the folder and draw said end through the folder, means on the clamp for distorting the body of the label to vary the relative length of the leading and trailing edges of the label, and means for adjusting the distorting means on the clamp to vary the extent of the distortion of the label body. 80
11. In a label folding machine, a clamp for gripping a label with opposite ends projecting therefrom, a pair of folders, means for moving the clamp between the folders edgewise of the label to draw said ends through the folders, and means on the clamp for distorting the label so that said ends will flare outwardly from the clamp 85
- 15 with respect to the axis of movement of the label. 90
12. In a label folding machine, a clamp for gripping a label with opposite ends of the label projecting therefrom, a pair of folders, means for moving the clamp between the folders edgewise of the label to draw said ends through the folders, and means on the clamp for distorting the label so that the leading edge of the label will be shortened. 95
13. In a label folding machine, a clamp for gripping a label with opposite ends of the label projecting therefrom, a pair of folders, means for moving the clamp between the folders edgewise of the label to draw said ends through the folders, and means on the clamp for distorting the label so that the leading edge of the label will be shorter 100
- 25 than the trailing edge. 105
14. In a label folding machine, a clamp for gripping a label with opposite ends of the label projecting therefrom, a pair of presses, a pair of folders, means for moving the clamp edgewise of the label between the folders and the presses to draw said ends through the folders and on to the presses, means on the clamp for crimping the leading edge of the label, and means for releasing the label from the clamp after it has been delivered to the presses. 110
- 35 15. In a label folding machine, a pair of folders, a clamp adapted to convey a label past the folders to fold opposite ends of the label, said clamp comprising a pair of jaws adapted to grip the label with said opposite ends projecting therefrom, one of the jaws being formed with a recess, a die carried by the other jaw and adapted to project into the recess to crimp the label. 115
- 45 16. In a label folding machine, a pair of folders, a clamp adapted to convey a label past the folders to cause opposite ends of the label to be folded, said clamp comprising a pair of jaws adapted to grip the label with said opposite ends projecting therefrom, one of the jaws being formed with a recess, a die carried by the other jaw and adapted to project into the recess to crimp the label, and means for adjusting the die transversely with respect to the length of the label. 120
- 55 17. In a label folding machine, a pair of folders, a clamp movable between the folders and adapted to draw the ends of a label through said folders to fold the same, said clamp comprising a pair of jaws for gripping the label with said ends projecting therefrom, one of the jaws being formed with a pair of slots transversely disposed with respect to the label, and a U-shaped die carried by the other jaw and adapted to project into the slots to crimp the label, the legs of the die having tapered ends. 125
- 60 18. In a label folding machine, a pair of folders, a clamp movable between the folders and adapted to draw the ends of a label through said folders to fold the same, said clamp comprising a pair of jaws for gripping the label with said ends projecting therefrom, one of the jaws being formed with a pair of slots extending toward the leading edge of the clamp, a two legged die carried by the other jaw and adapted to project into the slots to crimp the label, the legs of the die having tapered ends so that they will project more deeply at one end of the slots than the other, and means for adjusting the die lengthwise of the slots. 130
19. In a label folding machine, a pair of folders, a clamp movable between the folders and adapted to draw the ends of a label through said folders to fold the same, said clamp comprising a pair of jaws for gripping the label with said ends projecting therefrom, one of the jaws being formed with a pair of slots, a pair of projections carried by the other jaw and adapted to enter the slots to crimp the forward side of the label, said jaws being formed with marginal toothed ribs adapted to grip the rearward side of the label. 135
20. In a label folding machine, a pair of folders, a clamp movable between the folders and adapted to draw the ends of a label through said folders to fold the same, said clamp comprising a pair of jaws, one of the jaws being formed with a pair of slots, a U-shaped die carried by the other jaw and adapted to project into the slots to crimp the forward side of the label, said jaws being provided with means for gripping said forward side centrally and also with means for gripping the rearward side of the label adjacent said ends. 140
21. In a label folding machine, a pair of folders, a clamp movable between the folders and adapted to draw the ends of a label through said folders to fold the same, said clamp comprising a pair of jaws for gripping the label with said ends projecting therefrom, the lower jaw being formed with a pair of slots extending in the direction of motion of the clamp, a pair of projections in the upper jaw adapted to enter the slots more deeply near their forward end than their rearward end, the lower jaw being also formed with a pair of grooves in its upper face leading from the slots to the leading edge of the jaw. 145

GUSTAVE A. PIEPENBRING. 135
